UNITED STATES PATENT OFFICE.

SIDNEY REYNELL SMITH, OF LONDON, AND JOHN SAVIN, OF LIVERPOOL, ENGLAND,
ASSIGNORS TO AUTOMATIC ELECTRIC COMPANY, OF CHICAGO, ILLINOIS, A COR-
PORATION OF ILLINOIS.

AUTOMATIC TELEPHONE SYSTEM.

Application filed January 3, 1921. Serial No. 434,857.

To all whom it may concern:

Be it known that we, SIDNEY REYNELL SMITH and JOHN SAVIN, both subjects of the King of Great Britain and Ireland, and residents of London, England, and Liverpool, England, respectively, have invented certain new and useful Improvements in Automatic Telephone Systems, of which the following is a specification.

- 10 The present invention relates to improvements in calling devices for automatic telephone systems, of the general type wherein a rotatable dial is used to produce series of controlling impulses for the automatic switches; and the object of the invention is to provide improved means for regulating the interval which elapses between the generation of successive series of impulses.
- Reference is here made to Patent No. 20 1,444,777, issued to Blessing, Feb. 13, 1923, of which the present invention is an improvement. The feature of the Blessing calling device is the provision of a member adapted to be moved by the finger during 25 the setting operation to lock the impulse generating mechanism, for instance, by inserting an obstruction in the path of a pin, or its equivalent projecting from the shaft of the governor so that the finger has to be removed before the impulses can be generated.

One of the features of the present invention is the provision of a movable member adapted to be moved to prevent the transmission of impulses and to return slowly 35 under the control of a dashpot, or its equivalent. By arranging that the movable member is set in action immediately after the preceding series of impulses have been transmitted, i. e. by arranging that at the very commencement of the setting operation the movable member is moved to lock the impulse generating mechanism and subsequently is released after a limited movement 40 of the finger hold dial, say the space of one finger hole, it is possible to obtain a calling device which has the important feature that a delay between succeeding sets of impulses only occurs when the time between succeeding sets of impulses would otherwise be such as to endanger the proper functioning of the switching apparatus responding thereto.

For instance, it is found that it is possible to set up the dial to transmit one, two, three,

and possibly four impulses in so short a 55 time as to give an incorrect functioning of the exchange apparatus, but there is little or no danger when the dial is set up to transmit nine, or ten digits. Previously it has been usual to add to the setting up time 60 whether the number to be transmitted was large or small; this is obviously wasteful and by means of the present invention it is possible to arrange that only when it is absolutely essential to the proper functioning 65 of the exchange apparatus is a delay introduced.

A further feature of the present invention consists of a movable member adapted to be moved at the latter end of the setting 70 operation to prevent the generation of impulses until the movable member is restored to its normal position. By arranging that the movable member short circuits the impulse springs and, further, that it is adapted 75 to yield over a space of two or more fingerholes it is possible to arrange that the return of the movable member is controlled by the same governor as is used for regulating the generation of impulses and that a 80 delay may be obtained without increasing the size of the dial.

Further details and features of the present invention will be best appreciated by referring to the accompanying drawings in 85 which:—

Figures 1, 2, and 3 show one construction of calling device in which the movable finger stop effects the locking of the impulse generating mechanism. Figure 1 shows a 90 front view while Figures 2 and 3 show rear views with the movable finger stop in two different positions. Figures 4 and 5 show front and rear views, respectively, of another construction whereby unnecessary delay between the transmission of successive series of impulses is avoided; and Figures 95 8, 6, and 7 show inverted plan, sectional elevation, and section on line A-B, respectively, of a third construction whereby while retaining the features of the first construction an arrangement is provided for controlling the return of the movable member by the same governor as is employed for regulating the generation of impulses.

Referring to Figures 1, 2, and 3, the calling device comprises the usual dial or finger hold plate 1 adapted to be rotated in a clock-

wise direction by inserting a finger or pencil in one of the holes shown and moving up to a rigid stop. The finger hold plate 1 on being rotated winds up a spring 2 which tends to restore it to its original position. On being released, by means of the usual ratchet mechanism (not shown), the interrupter cam 3 and governor 4 are engaged with the finger hold plate and rotate with it. The interrupter cam 3 separates the interrupter springs 5 intermittently a number of times depending on the number opposite the hole in which the finger was first inserted, while the governor regulates the speed at which the impulses are generated so that they are most suitable for the correct operation of the automatic switches.

Such operation and construction is well known but is modified in the present construction by providing in place of a rigid stop a movable stop 6 adapted to yield until it engages with the side of the guide plate 7. The stop 6 is pivoted on the underneath side of the dial about the projections 8, used for regulating the tension of spring 2, by means of an annular disc 9 which is held to the rear plate 10 partly by means of the screw 11 and partly by the guide plate 7. Through the governor shaft a pin 12 is forced projecting about equally on each side and adapted to engage with the annular disc 9 except when this disc is in the position shown in Figure 2, as then the pin comes opposite a slot 13 provided in the disc 9. The operation may then be briefly described as follows:—When the finger in setting up the dial comes into engagement with the finger piece 6 it carries it round through a position such as shown in Figure 3 to a stop due to the finger piece 6 engaging with the end of the guide plate 7. During this time the slot 13 in the annular disc 9 has been moved in the direction shown in Figure 3. Now if the finger is not removed, even if the finger assists, the dial cannot move backwards, because the pin 12 engages with the disc 9 and cannot rotate as this obstruction is in that part of the gearing which runs at the highest speed and includes the wormwheel 14. Consequently the finger must be removed before any other operation can take place. Once the finger is removed the annular disc is restored to its normal position as shown in Figure 2 by means of the spring 15 and then when it reaches this position, and not before, the pin 12 on the governor shaft is released and the finger hold plate can return, rotating with it, by means of the ratchet device, the interrupter cam 3 and the governor 4.

Obviously it is sometimes desirable to control the time between successive impulses somewhat more positively than described in the foregoing, and for this purpose a dashpot or other time regulating device may

be employed, for controlling the return of the locking member.

Referring to Figure 5, this shows the rear view of another construction of dial which differs from the previous construction in that the annular disc 9 is cut off short at the stem 16 so that the finger piece 6 is eliminated being replaced by the usual fixed finger stop 17. On the disc 9 a leaf spring 18 is secured having one end bent in a suitable curve so as to be engaged by the locking dog 19. This locking dog 19 is usually provided for the purpose of locking the pinion 20 on the return of the finger-hold dial to its normal position and thereby preventing the further generation of impulses due to the inertia of the moving parts.

In addition to the other modifications mentioned, a dashpot 21 is provided pivoted to the plate 10 at 22 and to the disc 9 at 23. In its simplest form the dashpot may comprise a piston or rod 24 and a small cylinder 25 having therein a small aperture arranged to retard the return of the disc 9 under the control of the spring 15 as will be readily appreciated. Obviously the dashpot might be replaced by an equivalent device performing the same function without departing from the spirit of the invention.

The operation is as follows:—

A finger is inserted in one of the holes in the finger hold plate and rotated clockwise as usual; shortly after the commencement of the movement the dog 19 engages with the downturned edge of the spring 18, thereby causing the disc 9 to move against the spring 15 so that the slot 13 is no longer under the pin 12, (Figure 2). Eventually the spring 18 engages with the end of the slot 26 in the plate 10 so that it can move no further; at this instant, the dog 19 is enabled to pass the spring 18 which is forced outwards sufficiently to permit this and the dog 19 is then carried round with the dial plate. Now obviously as soon as the dog 19 had passed the spring 18, the disc 9 is free to return to its normal position but slowly under the combined control of the spring 15 and the dashpot action of rod 24 in cylinder 25. This return is regulated so as to take up a definite interval of time corresponding to the maximum time required between the transmission of successive series of impulses. Consequently the backward rotation of the dial and the generation of impulses is rendered impossible until this time interval has elapsed. Consequently if the finger reaches the finger stop 17 before this time has elapsed, the dial will not return until it has, while if the finger reaches the finger stop 17 after this time has elapsed, the dial can immediately rotate backwards and generate impulses. The dog 19 is so shaped as to pass the leaf spring 18 readily on its return movement.

It will be appreciated, therefore, that by this construction it is impossible to generate successive series of impulses without these being separated by the correct time interval required for the system; while at the same time, no waste of time nor unnecessary delay need occur.

Another improvement is illustrated in Figures 6, 7, and 8, and differs from the preceding construction as will be appreciated from the following description.

The dial plate 1 is fitted with a stop 27 on its under side in place of the dog 19 shown in Figure 5; to its shaft 29 is secured a ratchet wheel 28; while between the ratchet wheel 28 and the plate 1 a finger piece 30 is adapted to move freely about the shaft 29.

On the underside of the finger piece 30 is an arm 31 extending as shown in Figure 6 to the under side of the rear plate 10; on this arm a ball or like member 32 is fitted in such a manner as to have a certain freedom of movement in a radial direction only. For instance, the ball 32 may be slotted and if desired be forced outwards under spring tension, this spring in the case of a ball, however, is not essential.

Secured to the rear plate is a guide plate 33 which serves to control and direct the position of the ball as will be explained later. The movement of the finger piece 30 is limited by means of stops 34 and 35 secured to the edge of the rear plate 10 and extending into the path of the finger piece 30.

On the under side of the rear plate a pair of contact springs 36 and 37 are mounted. These are normally separated but as soon as the finger piece 30 is moved from normal position they make contact to short circuit the interrupter springs 5 (see Figure 2). The annular disc 9 is identical with that shown in Figure 2 except that its connection with the finger piece is severed and further it is provided with a pin 38 in the path of the extension piece 39 of the arm 31 for a purpose to be hereafter described. Having described the features of novelty in this latter construction, a description will now be given of the operation of the device.

Suppose it is desired to generate 10 impulses, the operator will insert his finger in the hole in the finger hold plate 1 opposite the numeral 0 and will then move the plate in a clockwise direction until it comes to a stop. Prior to reaching the stop the finger will have engaged with the finger piece 30 moving it with the ball 32 and the arm 31 with its extension piece 39. The ball is so arranged that due to the contour of the guiding plate it is forced into a recess in between the ratchet teeth; the ratchet teeth being arranged as to permit of this at this instant. Preferably there are the

same number of ratchet teeth on the wheel 28 as there are ratchet teeth on the crown wheel 40 which is provided in a well known type of dial switch for providing the one way clutch between the finger hold plate and the impulse generating mechanism. By this means an accurate relationship between the location of the finger piece with the finger hold plate can best be assured.

The movement of the fingerpiece 30 through the arm 31 and its extension piece 39 effects the short circuiting of the interrupter springs by means of the springs 36 and 37 which close as soon as extension piece 39 is moved from engagement with spring 36; subsequently the extension piece 39 engages with pin 38 on annular disc 9 and causes this disc to rotate until the finger piece 30 engages with the stop 35 when everything comes to rest.

The movement of the annular disc 9 has effected the locking of the governor so that not until it returns to its normal position can the finger hold plate return. This can only be attained by the operator removing his finger from the hold when the disc immediately restores under the control of the spring 15, and brings with it the finger piece 30. As will be seen, the guide plate 33 at this point is further away from the ratchet wheel so that the ball can pass the ratchet tooth which would otherwise obstruct the return of the finger piece. As soon as the disc 9 reaches its normal position the governor is released and the finger hold plate begins to return. At this instant, however, the ball 32 on the finger piece 30 is at a constricted part of the passage between the guide plate 33 and the ratchet wheel 28 and, further, is partially lying in a recess between the teeth. The consequence is that the finger piece returns with the finger hold plate under the control of the governor. At the same time the interrupter springs are being broken and closed, but this is of no effect at this time as they are short circuited by the springs 36 and 37.

In due course the finger piece 30 reaches its normal position pressing against the stop 34, the extension piece 39 breaks the short circuit across the interrupter springs while the ball 32 is pressed into the enlarged space allowed by the guide plate 33 at this position and the effective generation of impulses commences, which continues until the stop 27 strikes against the finger piece 30 and further movement is prevented.

It will be appreciated that a similar effect will be produced whatever the number of impulses transmitted, but the number 10 was taken as an example so that it might be appreciated that actually the finger hold plate is moved through more than a complete revolution; and further that the stop 27 per-

mits this, whereas the pinion 20 would obstruct the path of the dog 19 previously used for the same purpose. Further, it will be appreciated that while generating ten impulses actually the finger hold plate moves through a distance corresponding to fourteen or even more impulses and this has been attained without appreciably increasing the size of the finger hold plate or the dial generally. Again by this construction it is possible to use the same governor as controls the generation of impulses to regulate the return of the movable member to its normal position.

Having now particularly described and ascertained the nature of our said invention, what we claim is:—

1. In a calling device for automatic telephone systems, a manually operable calling dial, a finger stop limiting the movement of said dial, impulse sending mechanism operated by said dial on its return, locking means operating to delay the return of said dial and effective to introduce a minimum time interval between successive actuations of said dial, and cooperating means between the said dial and locking means whereby the delay is omitted in case the normal time interval between successive actuations of said dial exceeds the minimum.

2. In an impulse sending device, a finger hole dial rotatable forward and back, an annular member having a resilient extension, said extension adapted to be coupled to the dial to move said member for a certain period of travel at the end of which it is automatically released, means for returning said member to its initial position independently of the dial, and means whereby said member delays the return of the dial.

3. The combination, in an impulse transmitter, of a finger hole dial movable in a clockwise and counter clockwise direction, a fixed finger stop for limiting the clockwise movement of said dial, and means operated during the clockwise movement of the dial for delaying the counter clockwise movement of the dial only when the clockwise movement of the dial requires less than a predetermined period of time.

4. The combination, in an impulse transmitter of a finger hole dial movable in a clockwise and counter clockwise direction, a fixed finger stop for limiting the clockwise movement of said dial, and means operated during the clockwise movement of the dial for in certain instances delaying the counter clockwise movement of the dial for a variable time dependent directly on the time consumed during the clockwise movement.

5. In a calling device, a finger hole dial capable of forward and backward movement, interrupter mechanism operated by said dial on its backward movement, an au-

tomatic moveable stop having normal and off normal positions, means for moving said stop off normal on the forward movement of the dial, means for delaying the return of said stop for a definite time, and means for preventing the backward movement of the dial until the stop is fully restored.

6. In an impulse sending device, a rotatable finger hole dial operable in a variable forward and backward movement, a rotatable member adapted to be automatically operated and released by the dial during its forward movement, means co-operating with said member for locking the dial against return while said member is off normal, and means for controlling the restoration of said member to delay the backward movement of the dial for a definite time.

7. In a calling device, a dial adapted to be set in accordance with the digits in a called number by forward rotation thereof, sending mechanism operated by said dial on its return rotation, and means effective only in case said dial is set in accordance with a low digit for delaying the return of the dial.

8. In a calling device, a dial adapted to be set in accordance with the digits in a called number by forward rotation thereof, sending mechanism operated by said dial on its return rotation, means tending normally to cause the return rotation of the dial as soon as the same is released on the completion of the setting movement, and means for automatically delaying the return of the dial only in certain instances.

9. In a calling device, sending mechanism, manually operable means for setting said mechanism in accordance with any digit, means normally tending to operate said mechanism as soon as the setting is completed, and means for automatically delaying the operation only in case the mechanism is set for particular digits.

10. In a calling device of the type in which the setting operation must take place after the generation of one series of impulses to effect the generation of a new series of impulses, a finger hole dial, means controlled by said dial after the cessation of one series of impulses for inserting a rigid locking obstruction in the impulse mechanism to prevent the generation of a succeeding series of impulses until a definite minimum time has elapsed.

11. In a calling device of the dial type in which a setting operation must take place after the generation of one series of impulses to effect the generation of another series of impulses, means for preventing the impulse generating means from being actuated for a predetermined time, and an auxiliary member for determining the period of time the impulse generator is prevented from being actuated.

12. In a calling device of the dial type in which a setting operation must take place after the generation of one series of impulses to effect the generation of a new series of impulses, an impulse mechanism locking member, means for positioning said member in the path of the impulse mechanism during the setting movement of the dial, means for moving said member from the path of the impulse mechanism, and a delaying device preventing the restoration of said rigid locking member for a predetermined period.
13. In a calling device of the dial type, impulse mechanism, a disc member for preventing the impulse mechanism from operating while said disc is in an off normal position, means for moving said disc in an off normal position during the setting movement of the dial, means for restoring said disc to normal to render the impulse mechanism effective, and means for delaying the restoring movement of said disc for a definite period.
14. In an impulse transmitting device, a finger hole dial, impulse springs, means for operating said springs, a disc member in said device for delaying the operation of said springs for a definite period preceding the transmission of a series of impulses, and means controlled by said dial for rendering said disc member effective for the purpose set forth each time the dial is operated.
15. In an impulse device, impulse mechanism, a dial for setting said mechanism in readiness to transmit impulses, a blocking member, means for operating said member during the setting movement to prevent the immediate generation of impulses, means for restoring said member, and means for delaying the restoration for a definite period.
16. In an impulse transmitting device, impulse mechanism, means including a dial for setting said mechanism in motion to transmit impulses, means comprising a blocking member controlled by the dial during the setting movement for preventing the operation of said impulse mechanism, means for restoring said blocking member to normal, and means for definitely delaying the restoring operation of said member.
17. A calling device in which a setting operation must take place after the generation of one series of impulses to effect the generation of a fresh series of impulses, a finger hole dial, mechanism for transmitting impulses, an auxiliary part, means controlled by the finger hole dial for interposing said auxiliary part in the mechanism to prevent the generation of a fresh series of impulses, means for automatically withdrawing said auxiliary part, and a speed regulating device for preventing the withdrawal of said part for a predetermined time.

Signed by us at Liverpool, England, this 2nd day of December, 1920.
